BOILER CLEANER

Norman L. Snow, New Canaan, Conn., assignor
to Diamond Power Specialty Corporation, De-
troit, Mich., a corporation of Michigan

Application September 28, 1931, Serial No. 565,437

13 Claims. (Cl. 122—392)

The invention relates to boiler cleaners and refers particularly to a cleaner of the type wherein jets of cleaning fluid are discharged as from a nozzled tube adjacent the surfaces of the boiler to be cleaned.

The invention numbers among its objects the provision in a boiler cleaner of means for adding to the cleaning fluid ordinarily used, a second cleaning substance of different properties. The invention also embraces means for cooling the nozzled tube, this being particularly applicable in those cases where the tube extends adjacent the boiler surfaces in regions of high temperature.

Other objects and advantages of the invention will become more apparent as the following description proceeds, particularly when reference is had to the accompanying drawings, wherein:

Figure 1 is a side elevation of a boiler cleaner constructed in accordance with the teachings of the invention, applied to a tubular boiler of conventional construction;

Figure 2 is an enlarged detail of the connection between the second cleaning fluid pipe and its supply elbow;

Figure 3 is an alternate arrangement of the detail shown in Figure 2;

Figure 4 is an enlarged detail of the control valve for the second cleaning substance;

Figure 5 is a view partly in section and partly in elevation, along the line 5—5 of Figure 1, with the bell crank mechanism misplaced, to show the operating mechanism for the aforementioned control valve;

Figure 6 is a view in elevation showing a modified control valve for the second cleaning substance.

Referring then particularly to the drawings wherein like reference characters designate corresponding parts throughout all views, the numeral 1 designates an automatic valved boiler cleaner operating head of conventional construction. The head is supported from boiler wall 4 by floater 7 fixed in turn to wall box 6 mounted in opening 5 in the side wall. Element 2 provided with nozzles 8 extends adjacent the boiler tubes 3 from which it may be supported in any desired manner not shown. The nozzles 8 correspond substantially in number to the spaces adjacent the aforesaid boiler tubes 3.

Element 2 is joined by coupling 27 to swivel tube 39 which is rotatably journaled in the operating head. Fixed to the swivel tube 39 is the large gear 11 adapted to be actuated by pinion 10 which, in turn, may be actuated

through suitable connections by the sheave wheel 9. Mounted on the face of gear 11 is the cam 12 adapted upon rotation to move the trigger 14 to depress valve stem 17, opening valve 16, thus admitting a cleaning fluid such as air or steam from the supply line 38 to the head and thence to the element 2. The trigger 14 is supported in the clevis 15 formed integrally with the gooseneck 13.

In my prior application, Serial 692,094 means are shown for automatically admitting to the boiler cleaner operating head a second cleaning fluid such as water, possessing properties different from the cleaning fluid ordinarily used, such as steam or air. The present invention utilizes this basic principle, employing a different mechanism and providing means for insuring distribution of said second cleaning substance uniformly along the length of the element.

At the upper portion of the gooseneck 13 is provided an enlargement 18 to one end of which is fixed an elbow 19 through which the second cleaning substance is supplied. Valve 22 is provided in the supply line, this valve being automatically actuated upon rotation of the element a predetermined amount to supply the second cleaning substance. A conventional valve 25 for manual operation is further provided in the supply line 26 whereby the second cleaning substance may be manually controlled as desired.

As best shown in Figure 2, a second nozzled tube 20 is fixed as by welding to elbow 19. This nozzled tube 20 extends centrally of the element 2, nozzles 21 being provided along its length for the discharge of the second cleaning substance. Tube 20 may be supported approximately centrally of element 2 as by loosely fitting spiders not shown.

Operation of valve 22 may be effected by trigger 14 as best shown in Figure 5, this trigger thus serving to control the supply both of the principal cleaning substance and the second cleaning substance. Bell crank mechanism 40 is fitted to extension 32 of trigger 14 and may be actuated by movement of the trigger to move the valve stem 23 laterally away from the valve seat 24 as shown in Figure 4 to admit the second cleaning substance.

In the arrangement just described the distributing pipe for the second cleaning substance is held stationary while the nozzled element 2 is rotated around it, the preferable position of

the inner tube 20 is such that the nozzles 21 point upwardly.

In Figure 3 is shown a connection of tube 20' on the elbow 19' such that the distributing pipe 20' may rotate with the element 2'. Spider 28 is attached as by welding to tube 20', this spider being held by set screw 29 passing through coupling 27' between the element 2' and the swivel tube 39, both of which are suitably secured in said coupling.

The invention, moreover, resides in the provision of means for supplying through the arrangement hereinbefore described a cooling medium such as water to the boiler cleaner element. The cooling medium such as water may be supplied in amounts depending upon the location of the boiler cleaner element and the temperature to which it is exposed.

By reference to Figure 4 an auxiliary valve port 31 will be noted with which valve stem 30 co-operates. This auxiliary valve provides means to admit to the boiler cleaner element a regulable supply of water at all times.

Thus by manipulation of valve stem 30 water may be admitted to the boiler cleaner element in an amount sufficient to cool the boiler cleaner element to a temperature where it will live satisfactorily in any given location. It will be found convenient in many cases to admit to the element water in just sufficient amount to be completely evaporated in the boiler cleaner element without flow of water therefrom.

In Figure 6 is shown an alternative arrangement of the control valve for the cooling fluid wherein the auxiliary valve 35 is located in a by-pass line 33 around the main body of the valve 22'. This auxiliary valve may be controlled by thermostatic element shown at 36 which element is actuated by thermometer 34 40 which may be conveniently located in the breeching or uptake 37 from the boiler furnace. The purpose of this arrangement is to prevent the flow of cooling fluid, such as water, through the by-pass and into the boiler cleaner element 45 2 at periods when the boiler is banked or off the line. Under these circumstances the temperatures in the uptake 37 will be much lower than when the boiler is in operation, the thermostatic control being so arranged as to close the valve 35 under these low temperature conditions and to open it under higher temperature conditions in the breeching when the boiler is normally operating. Automatic means are thus provided for insuring the shutting off of 50 the cooling fluid supply to the blower element when the boiler is not in normal operation.

For the sake of convenience the invention has been described as comprising a boiler cleaner adapted for cleaning parts of a boiler. It will be apparent, however, that the invention may be incorporated in devices for cleaning similar types of apparatuses, and it is to be therefore understood that the term "boiler" wherever used in the specification or claims is to be construed as meaning a heat transfer apparatus or fluid heater of any character, while the term "boiler cleaner" is to be construed as meaning a cleaner for any such apparatus.

While the invention has been described with considerable detail, it is to be clearly understood that the description is for the purpose of illustration only and is not definitive of the limits of the inventive idea. The right is therefore reserved to make such changes in the details of construction and arrangement of parts

as will fall within the purview of the attached claims.

What I claim as my invention is:

1. In a boiler cleaner, a source of supply of cleaning fluid, a rotatable tube connected to said source of supply of cleaning fluid and provided with nozzles for discharging said cleaning fluid, a source of supply of a second fluid, means to conduct said second fluid to said rotatable tube including a valve provided with two ports, one of said ports being normally open, and means dependent upon rotation of the nozzled tube for uncovering the other of said ports. 80

2. In a boiler cleaner, a source of supply of cleaning fluid, a tube provided with nozzles for the discharge of said fluid, a source of supply of a cooling fluid, means to conduct said cooling fluid to said tube including a valve, and means dependent upon the temperature in said boiler setting for controlling the actuation of said 95 valve. 90

3. In a boiler cleaner, a source of supply of cleaning fluid, a rotatable tube provided with nozzles for discharging said cleaning fluid, and means to supply a second fluid having cleaning 100 and cooling properties to said tube including two valved openings, one of which is automatically controlled by the rotation of said tube and the other of which is constantly open to insure a constant supply of said second fluid to the said 105 tube. 100

4. In a fluid heater cleaner, a blower element having nozzles for discharging a cleaning fluid, means for admitting a cleaning fluid to said blower element for discharge therefrom, means operating to admit a second fluid to said blower element in timed relation to the admission of the cleaning fluid to the blower element, and means operable independently of the admission of cleaning fluid to said blower element for 115 maintaining a constant supply of said second mentioned fluid to said blower element. 110

5. In a fluid heater cleaner, a blower element having nozzles for discharging a cleaning fluid, a valve controlling the admission of cleaning 120 fluid to said blower element, a source of supply of a second fluid having cleaning and cooling properties, means operating upon the opening of said valve to admit a substantial quantity of said 125 second fluid to said blower element for discharge therefrom with the cleaning fluid, and means operable independently of the actuation of said valve for admitting said second mentioned fluid to the blower element irrespective of the supply 130 of cleaning fluid to the element. 130

6. In a fluid heater cleaner, a movable blower element provided with nozzles for discharging a cleaning fluid, means for supplying a cleaning fluid to said blower element, a source of supply of a second fluid, a valve for controlling the admission of said second fluid to the blower element, means for actuating said valve in timed relation to the movement of the blower element, and means providing a by-pass around said valve to insure a constant supply of said second 140 fluid to the blower element irrespective of the movement thereof. 135

7. In a boiler cleaner, a source of supply of cleaning fluid, a tube provided with nozzles for discharging said cleaning fluid, and means to apply a liquid to the interior of said nozzled tube to cool the same by evaporation of the liquid, said means operating in dependence upon the temperature of the boiler gases. 145

8. In a fluid heater cleaner, a blower element, 150

- means for supplying cleaning fluid to said blower element under sufficient pressure to effect a cleaning operation upon discharge of the cleaning fluid from the blower element, and means 5 operating during the intervals when the cleaning fluid is not being supplied to the blower element to discharge a cooling fluid against said blower element at points throughout the length thereof in such a manner that a substantial portion 10 of said blower element is contacted by said cooling fluid.
9. In the fluid heater cleaner, a blower element, means for supplying cleaning fluid to said blower element under sufficient pressure to effect 15 a cleaning operation upon discharge of the cleaning fluid from the blower element, and means disposed within said blower element operating during the intervals when the cleaning fluid is not being supplied to the blower element 20 to discharge a cooling fluid against said blower element at points throughout the length thereof in such a manner that a substantial portion of said blower element is contacted by said cooling fluid.
- 25 10. In a fluid heater cleaner, a blower element, means for supplying a cleaning fluid to said blower element under sufficient pressure to effect a cleaning operation upon discharge of the cleaning fluid from the blower element, and 30 means including a nozzled tube disposed within
- said blower element operating during the intervals when the cleaning fluid is not being supplied to the blower element to discharge a cooling fluid against said blower element at points throughout the length thereof in such a manner that a substantial portion of said blower element is contacted by said cooling fluid. 80
11. The method of cooling a fluid heater cleaner tube which is subjected to high temperature during the intervals when said tube is not discharging cleaning fluid which consists in discharging into contact with said tube just enough liquid to be completely evaporated by the heat of the tube. 85
12. The method of cooling a fluid heater cleaner tube which is subjected to high temperature during the intervals when the tube is not discharging cleaning fluid which consists in discharging into contact with the interior of the tube just enough liquid to be completely evaporated 90
13. The method of cooling a fluid heater cleaner tube which is subjected to high temperature during the intervals when the tube is not discharging cleaning fluid which consists in discharging into contact with said tube at spaced 100 points throughout the length thereof just enough liquid to be completely evaporated by the heat of the tube. 100
